FIG. 1 is a perspective view of a pump bulb with three lobes for an implantable penile prosthetic showing my new design;
 FIG. 2 is a front view thereof;
 FIG. 3 is a back side view thereof;
 FIG. 4 is a left side view thereof; the right side being a mirror image,
 FIG. 5 is a top view thereof; and,
 FIG. 6 is a bottom view thereof.
 In FIGS. 1-5 the broken lines illustrate conduits connected to the pump bulb and form no part of the claimed design.
